AUTOMATIC CAM TRIP

Arthur S. Caswell, Philadelphia, Pa., assignor to
 I-T-E Circuit Breaker Company, Philadelphia,
 Pa., a corporation of Pennsylvania

Application September 19, 1950, Serial No. 185,573

9 Claims. (Cl. 200—50)

1

My present invention relates to draw-out type circuit breakers of the type adapted to be inserted into and withdrawn from a compartment and movable between an operative and a test position; and more particularly to an automatic tripping device adapted to trip the circuit breaker automatically on the initiation of the draw-out movement of the circuit breaker so that interruption of or the establishment of a current path and extinguishment of the arc will take place at the circuit breaker contacts which are designed for this operation and not at the disconnects which are designed only to carry current and not to interrupt current.

My invention contemplates an improvement of the circuit breakers disclosed in Patent Nos. 2,611,838, issued September 23, 1952, and 2,613,299, issued October 7, 1952, wherein the racking bar is provided with an extension carrying a cam roller; the circuit breaker housing is provided with a slotted cam cooperating with the roller.

The racking bar mounted on the circuit breaker is stationary with respect to the enclosure compartment during the racking-in or -out of the circuit breaker; that is, the racking bar is usually connected to a screw so that the screw may rotate with respect thereto while it has longitudinal movement with respect to the racking bar.

Thus, when the racking bar is securely anchored in the compartment, rotation of the screw by an appropriate tool or handle will cause the circuit breaker to move in or out with respect to the enclosure compartment.

The cam is arranged so that when depressed in a counter-clockwise direction it will rotatively operate the tripper bar of the circuit breaker to trip the circuit breaker open. The cam has a slot engaged by the cam roller, the slot being so designed that the cam will be depressed in all horizontal positions of the circuit breaker between the fully racked-in and fully racked-out positions.

Therefore, on initiation of a racking out operation, if the circuit breaker has not already been tripped open, it will automatically be tripped open before the disconnect contacts have disengaged and will be locked in tripped position until the fully racked out or test position is reached.

Heretofore the cam was mounted on the cubicle to engage the latch shaft extension mounted on the circuit breaker. Any variation in dimension in the circuit breaker or the cubicle resulted in misoperation. In addition the circuit breakers in switchgear are required to be interchangeable. Any circuit breaker must enter all

2

cubicles of any installations and the interlocking must work. It is much easier to maintain this operation when the cam and the latch extension are an integral part of the circuit breaker and adjusted to that breaker. Variation in dimension of the cubicle no longer affects the operation. Interchangeability is easier to secure and more positive and safe. Accordingly an object of my invention is to provide a mechanical interlock integral with each individual drawout circuit breaker so that interchangeability of each circuit breaker within all similar circuit breaker compartments will not be operatively affected by slight variations in individual adjustments of aforementioned interlock device.

A further object of my invention, therefore, is the provision of novel automatic tripping means for a circuit breaker operable on the initiation of the racking-in or the racking-out operation.

Another object of my invention is the provision of automatic trip means for a draw-out circuit breaker which will maintain the circuit breaker in trip position during the racking out operation so that the circuit breaker cannot be closed at any position other than the fully racked-in or "Operative" position or the fully racked-out of "Test" position.

Another object of my invention is the provision of a cam roller on the racking bar and cam on the drawout circuit breaker, the cam being operable by the roller to trip the circuit breaker automatically on the initiation of either of the racking movements.

The foregoing and many other objects of my invention will become apparent in the following description and drawings in which:

Figure 1 is a schematic view in perspective of the racking bar, roller, cam and trip unit of my invention.

Figures 2, 3, and 4 are successive side views of the cam, roller and trip bar showing, respectively, the fully racked in, the partially withdrawn and the fully racked out positions of the circuit breaker.

Figure 5 is a view in perspective of the circuit breaker showing the automatic trip unit mounted thereon.

Figure 6 is a side view partly in cross-section of the draw-out circuit breaker in the compartment in a partially racked out position intermediate the "Operative" and "Test" positions.

The circuit breaker 100 of Figures 5 and 6 is the circuit breaker described and shown in Patent No. 2,611,838, issued September 23, 1952, which, however, is used by way of example only

since my invention is applicable to other draw-out circuit breakers having trip mechanism which can be operated to trip position by rotational movement.

The racking bar 400 of Figures 1, 5, and 6 corresponds to the racking bar 400 of Figures 1, 10, 11 and 12 of the said patent; its operation requires no specific description here (and the description with respect to said figures is incorporated herein by reference).

It is sufficient to point out that racking bar 400 has a screw 10 mounted in opening 44 thereof in such manner that it may rotate with respect thereto while having longitudinal movement with respect thereto. The screw 10 is in rotatively free engagement with bearing 12 in the circuit breaker.

Consequently, when the circuit breaker is wheeled into the compartment 200 (Figures 5 and 6) and the racking bar 400 is engaged with the compartment 200 to be relatively stationary with respect thereto, rotation of end 15 of screw 10 (Figure 1) in housing 16 (Figures 5 and 6) will cause the circuit breaker to move in from the "Test" position to the "Operative" position and vice versa.

The circuit breaker has the trip mechanism 20 and contact structure 21 described in the said Patent No. 2,611,838 issued September 23, 1952, the essential element of which for this application is the latch bar 25 pivotal on shaft 26 and having a latch end 27 engaging trip shaft 28 adjacent the milled portion 29 thereof.

When shaft 28 is rotated clockwise with respect to Figure 1, latch end 27 of latch bar 25 will enter milled portion 29 of trip shaft 28 and the circuit breaker will trip open. If shaft 28 is held in this rotated position, the circuit breaker will remain tripped until the shaft 28 is premitted to return counterclockwise to its original position. Consequently, the circuit breaker, since it is trip-free, cannot be closed while shaft 28 is in the clockwise rotated position.

For purposes of the present invention, shaft 28 is extended at 28a to one side of the circuit breaker where it is provided with crank arm 30 keyed thereto. The crank arm 30 may be an extension of the well-known tripper bar which is operated by electromagnetic means to trip the circuit breaker.

The side wall 40 of the circuit breaker housing carries the cam 50 rotatably mounted on pin 51 carried by the side wall 40 or the frame of the circuit breaker.

The racking bar 400 has an adjustable stud 55 mounted therein which carries the vertically adjustable screw 56 which in turn carries the cam roller bar 57 normal to the racking bar. This form of mounting of the cam roller bar 57 permits adjustment thereof to locate the roller 60 relatively with the cam 50. Cam roller bar 57 has a bracket 61 which carries cam roller 60. Cam roller 60 rides in the cam slot 65 in cam 50.

Bracket 66 on side wall 40 is provided with parallel flanges 67, 68 having the aligned openings 69 and 70 in order to furnish a support for the cam roller bar 57 and thereby maintain the cam roller 60 in a rigid horizontal position.

The cam slot 65 as is seen more particularly in Figures 2, 3 and 4 comprises a substantially horizontal section 65a, a downwardly curved section 65b at the outer end and a downwardly curved section 65c at the inner end adjacent the pivot 51.

The downwardly curved section 65c is so positioned that when the circuit breaker is fully racked-out, the roller 60 will register with section 65c of slot 65 and raise the end 50a of cam 50 to a substantially horizontal or slightly raised position.

Likewise, the downwardly curved section 65b at the outer end is so arranged that when the circuit breaker is fully racked in, the cam roller 60 will register therewith and also raise the cam 50 to a substantially horizontal or slightly raised position with portion 502 of the cam 50 raised.

When, however, the circuit breaker is positioned intermediately between the "Operative" and the "Test" positions and the roller 60 is set at the horizontal section 65a of the slot 65, then the end 50a of the cam 50 will be depressed. Owing to the curvature of sections 65b and 65c of the slot with respect to section 65a of the slot 65, the roller 60 will register with the horizontal section 65a of slot 65 during virtually all of the travel of the circuit breaker between the racked-out or "Test" position and the racked-in or "Operative" position.

Also, immediately upon movement of the circuit breaker from the racked-in position and before the primary disconnect contacts 70-71 (Figure 6) have disengaged, the cam will be moved so that the roller 60 registers with section 65a of the slot and the cam 50 is depressed to rotate the crank-arm 30 to trip the circuit breaker.

It should here again be noted that the racking bar 400 is relatively stationary with respect to the compartment 200 and that, therefore, the roller 60 is relatively stationary with respect to the compartment 200 since it is supported solely from racking bar 400.

The remainder of the circuit breaker moves with respect to the compartment 200 on rotation of the screw 10 by a handle or other operating means associated with the end 15 of the screw 10 as above described.

The end 50a of the cam 50 registers with and bears upon the pin 80 connected to the crank arm 30 and is so arranged that when the cam 50 is raised the crank arm 30 and the milled shaft 28 are in the non-trip position of the circuit breaker mechanism but when the cam 50 is lowered by the engagement of roller 60 in slot sections 65a, the end 50a of the cam will press down the roller 60 on crank arm 30 of the trip shaft 28 and move the trip shaft 28 to the trip position.

Consequently, immediately upon initiation of the racking-out operation, the circuit breaker will automatically be moved to the trip position of the cam 50 and will remain in the trip position until the racking out operation is completed, at which time the roller moves into registry with slot section 65b permitting the cam to be raised once more and permitting the milled shaft 28 to move back to non-trip position.

Thus, the circuit breaker can be operated only in the fully-racked-out or fully racked-in position and is automatically tripped at any position therebetween and, therefore, will automatically be tripped upon any attempt to rack out the circuit breaker at a time when the circuit breaker is closed.

In the foregoing I have described my invention solely in connection with specific illustrative embodiments thereof. Since many variations and modifications of my invention will now be obvious to those skilled in the art, I prefer to be

bound not by the specific disclosures herein contained but only by the appended claims.

I claim:

1. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member mounted on said cubicle for securing said racking bar to said cubicle to permit movement of said screw and circuit breaker relative to said racking bar and cubicle for racking said circuit breaker into racked-in and racked-out positions; a cam mounted on said circuit breaker, a cam follower mounted on said racking bar engaging said cam, a cam follower bar connection from said cam follower to said trip mechanism, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by the racking out of said cam when said circuit breaker starts for operating said circuit breaker to its trip open position before said disconnects disengage and for positively maintaining said circuit breaker in its trip open position until said circuit breaker has been moved to its racked-out position.

2. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member for securing said racking bar to said cubicle to permit movement of said screw and circuit breaker relative to said racking bar and cubicle for racking said circuit breaker into racked-in and racked out positions; a cam mounted on said circuit breaker, a cam follower mounted on said racking bar engaging said cam, a cam follower bar connection mounted on said racking bar and providing a connection from said cam follower to said trip mechanism, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by said cam when the racking out of said circuit breaker starts for operating said circuit breaker to its trip open position before said disconnects disengage and for positively maintaining said circuit breaker in its trip open position until said circuit breaker has been moved to its racked-out position.

3. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member for securing said racking bar to said cubicle to permit movement of said screw and circuit breaker relative to said

racking bar and cubicle for racking said circuit breaker into racked-in and racked-out positions; a cam mounted on said circuit breaker, a cam follower mounted on said racking bar engaging said cam, a cam follower bar connection mounted on said racking bar and providing a connection from said cam follower to said trip mechanism, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by said cam when the racking out of said circuit breaker starts for operating said circuit breaker to its trip open position before said disconnects disengage and for positively maintaining said circuit breaker to its trip open position until said circuit breaker has been moved to its racked-out position, and an adjusting mechanism mounted on said circuit breaker for adjusting said connection to properly position said cam follower on said cam.

4. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member for securing said racking bar to said cubicle to permit movement of said screw and circuit breaker relative to said racking bar and cubicle for racking said circuit breaker into racked-in and racked out positions; a cam mounted on said circuit breaker, a cam follower mounted on said racking bar engaging said cam, a cam follower bar connection mounted on said racking bar and providing a connection from said cam follower to said trip mechanism, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by said cam when the racking out of said circuit breaker starts for operating said circuit breaker to its trip open position before said disconnects disengage and for positively maintaining said circuit breaker in its trip open position until said circuit breaker has been moved to its racked-out position, and an adjusting mechanism mounted on said racking bar for adjusting said connection to properly position said cam follower on said cam.

5. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member for securing said racking bar to said cubicle to permit movement of said screw and circuit breaker relative to said racking bar and cubicle for racking said circuit breaker into racked-in and racked-out positions, a circuit breaker operating mechanism mounted on said circuit breaker, a connecting bar from said operating mechanism to said trip mechanism, said bar being mounted on said racking

bar, said operating mechanism when said circuit breaker is moved relative to said cubicle operating through said connecting bar to operate said trip mechanism to trip said circuit breaker.

6. A circuit breaker constructed for movement into and out of a cubicle and having primary disconnect contacts, said circuit breaker having a circuit closed and a trip open position, a trip mechanism for operating said circuit breaker to its trip open position, a screw carried by said circuit breaker, a racking bar carried by said screw, a locking member for securing said racking bar to said cubicle to permit movement of said screw and circuit breaker relative to said racking bar and cubicle for racking said circuit breaker into racked-in and racked-out positions, a circuit breaker operating mechanism mounted on said circuit breaker, a connecting bar from said operating mechanism to said trip mechanism, said bar being mounted on said racking bar, said operating mechanism when said circuit breaker is moved relative to said cubicle operating through said connecting bar to operate said trip mechanism to trip said circuit breaker, and an adjusting mechanism on said racking bar for adjusting the connection of said connecting bar relative to said circuit breaker operating mechanism.

7. A circuit breaker having a trip mechanism constructed for movement into and out of a cubicle; a cam mounted on said circuit breaker; a cam follower engaging said cam, a racking bar, a cam follower bar providing a connection from said cam follower to said racking bar, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by said cam when the racking-out of said circuit breaker starts for operating said circuit breaker to its trip open position and for positively maintaining said circuit breaker in its trip open position until said circuit breaker has been moved to its racked-out position.

8. A circuit breaker having a trip mechanism and disconnect contacts constructed for movement into and out of a cubicle; a cam mounted on said circuit breaker; a racking bar; a cam follower bar providing a connection from said cam follower to said racking bar, said cam having a surface at one end thereof engageable by said follower when said circuit breaker is in its racked-in position and having a surface engageable by said follower at its other end when said circuit breaker is in its racked-out position and having a surface intermediate said position engageable by said follower so that said cam follower is instantly operated by said cam when the racking-out of said circuit breaker starts for operating said circuit breaker to its trip open position before said disconnects disengage and for positively maintaining said circuit breaker to its trip open position until said circuit breaker has been moved to its racked-out position; and an adjusting mechanism mounted on said circuit breaker for adjusting said connection to properly position said cam follower on said cam.

9. A circuit breaker constructed for movement into and out of a cubicle and having primary disconnect contacts, said circuit breaker having a circuit closed and a trip open position, a trip mechanism for operating said circuit breaker to its trip open position, a circuit breaker operating mechanism mounted on said circuit breaker, a connecting bar from said operating mechanism to said trip mechanism, said operating mechanism when said circuit breaker is moved relative to said cubicle operating through said connecting bar to operate said trip mechanism to trip said circuit breaker, and an adjusting mechanism for adjusting the connection of a cam follower bar relative to said circuit breaker operating mechanism, said cam follower bar being stationary with respect to said cubicle during the racking-in or out movements of said circuit breaker.
